UNITED STATES PATENT OFFICE.

JOSEPH H. TAUSCH, OF WAUKEGAN, ILLINOIS, ASSIGNOR OF ONE-HALF TO GEORGE GORTON, OF RACINE, WISCONSIN.

ADJUSTABLE AND CONVERTIBLE GATE.

1,168,233.

Specification of Letters Patent.

Patented Jan. 11, 1916.

Application filed January 21, 1915. Serial No. 3,428.

To all whom it may concern:

Be it known that I, JOSEPH H. TAUSCH, a subject of the Emperor of Germany, residing at the city of Waukegan, in the county of 5 Lake and State of Illinois, have invented certain new and useful Improvements in Adjustable and Convertible Gates, of which the following is a specification.

This invention relates to improvements in 10 gates in general, but has particular relation to fence gates of the adjustable type, which are by preference made of metal and are adapted for barring all kinds of stock, and cattle, as well as, sheep, pigs and hogs, yet 15 if desired, can be so adjusted as to permit the passage of the smaller animals while shutting out or barring the larger ones, and it consists in certain peculiarities of the construction, novel arrangement and operation 20 of the various parts thereof, as will be hereinafter more fully set forth and specifically claimed.

The principal object of the invention is to 25 provide a gate of the above named general character, which shall, as a whole, be simple and inexpensive in construction, strong, durable and efficient in operation, capable of being opened in either direction, adjusted bodily and vertically on its hinges or ad- 30 justed at an angle with respect to the ground without interfering with the hinges.

To accomplish these results, other objects 35 of the invention are to provide an improved hinge-member by means of which the gate can be bodily adjusted to the desired height and there securely maintained; to furnish an automatic-latch for engaging the free end of the gate, when the latter is swung in either direction, and locking the same in 40 its closed position; to supply simple yet effective means, or attachment for locking the parts of the gate in their normal positions, or in the positions they will assume when the gate is adjusted to its angular 45 position, or, in other words, to convert the gate into a rigid-frame gate or an adjustable frame one, or vice versa.

Still another object is to provide an im- 50 proved truss-brace for uniting the central portions of the upper and lower rails of the gate in such a manner that they will be strongly connected yet so as to permit of the necessary movement thereof in the angular adjustment of the gate.

55 Various other objects and advantages of

the invention will be disclosed in the subjoined description and explanation.

In the accompanying drawings, which serve to illustrate the invention—Figure 1 is a view in elevation of a gate embodying the 60 different improvements, and illustrating by continuous lines the normal position of the gate, and by dotted lines the positions the parts will assume when the gate is adjusted at an angle to the ground so as to permit 65 small animals, such as hogs and sheep, to pass thereunder; Fig. 2 is a plan view partly in section of the front end bar of the gate, showing the latch mounted thereon, and illustrating by dotted lines one of the positions to which it can be turned on the gate 70 bar, so that the arms thereof will automatically and positively engage the holding member therefor on the fence post at the front of the gate; Fig. 3 is a sectional view 75 taken on line 3—3 of Fig. 2, looking in the direction indicated by the arrows; Fig. 4 is a plan sectional view taken on line 4—4 of Fig. 3; Fig. 5 is a detached perspective view of the locking bolt or block for the latch 80 arms; Fig. 6 is an enlarged view of a portion of the upper part of the front bar of the gate and a part of the upper horizontal rail thereof, showing the attachment or means for rigidly holding the parts of the 85 gate with respect to one another, whether they occupy their normal positions or their adjusted positions; Fig. 7 is a cross sectional view taken on line 7—7 of Fig. 6, looking in the direction indicated by the 90 arrows; Fig. 8 is a similar view taken on line 8—8 of Fig. 6; Fig. 9 is a fragmental view partly in elevation and partly in section of a portion of the rigidly securing attachment, showing a modification in its 95 construction; Fig. 10 is a side view of a portion of the rear end bar of the gate, a part of the rear fence post showing the improved adjustable hinge secured to the latter and engaging the said gate bar; Fig. 11 is an inner face view of like parts; Fig. 12 is a vertical sectional view taken on line 12—12 of Fig. 11; Fig. 13 is a plan view of one of the hinge brackets; Fig. 14 is a side view of the truss-brace for the central portion of 100 the upper and lower rails of the gate showing the latter in cross section, but with the cross wires omitted; and Fig. 15 is an enlarged sectional view taken on line 15—15 105 of Fig. 14.

Like numerals of reference refer to like parts throughout the different views of the drawings.

The gate or fence post at the front or swinging end of the gate is indicated by the reference numeral 20, while 21 designates the gate or fence post at the rear end of the gate. The front post 20 is provided on its face adjacent to the gate with a vertically extended rod or tube 22, which is spaced from and secured to the post 20 by means of hollow extensions 23, through which and the member 22 are passed bolts which engage said post. This upright member or tube 22 is employed as a keeper for the arms of the latch, as will be presently explained. The rear post 21 has secured at suitable points, one above the other, on the face of the post adjacent to the gate, a pair of hinge brackets 24, which may be of the construction illustrated in Figs. 10 to 13 inclusive of the drawings. The gate consists of two upright end bars 25 and 26, which are pivotally united near their upper and lower ends by horizontally disposed tubes or rails 27 and 28 respectively. Each of the end bars 25 and 26 of the gate is by preference U-shaped in cross section and have their open portions presented toward each other. The ends of the rails or tubes 27 and 28 are by preference inserted between the walls of the U-shaped bars 25 and 26, and are secured in position by means of pivots 29, extended transversely through said bars and rails. A net work, indicated as a whole by the reference numeral 30, of intersecting wires or small rods forms the body of the gate, which is located within the space bounded by the end bars 25 and 26 and the upper and lower rails 27 and 28, and may be secured at one of its ends, preferably the front end, by extending the horizontal wires around the bar 25, and at its other or rear end by adjustable or screw bolts 31, extended through an upright 32 in engagement with one end of the net work 30 and engaging the rear bar 26 of the gate. By this means the desired longitudinal tension of the net work may be regulated and maintained. As shown in Fig. 1 of the drawings, the upper ends of the bars 25 and 26 project some distance above the upper rail 27 of the gate, and each of said bars has fitted thereon a cap 33, each of which is provided with an apertured extension 34, on its inner face, in which extensions the ends of the brace-wire or rod 35 is secured.

Mounted on the front gate bar 25 at a suitable point between its ends is a latch carrying bracket, which is designated as a whole by the numeral 36, and said bracket consists of two members 37, counterparts of one another, each having at opposite ends apertured lugs 38 for the reception of bolts 39, used for securing the members 37 to-

gether around the gate bar 25, as will be readily understood by reference to Fig. 2 of the drawings, from which view it will be understood that the inner faces of the members 37 of the bracket 36 are provided with recesses 40 of a shape that when said members are united they will correspond with the shape of the bar 25, which, in the present instance is U-shaped. However, the recesses 40 of the members 37 may be of other shapes than that shown, and said members may be secured to the bar 25 if the same is of other shape than U-shape, by any suitable means. Each of the members 37 of the bracket 36, is provided on its outer surface between its upper and lower ends with a curved groove, which, when said pieces are joined together, form a bearing 42 (see Fig. 4) for the curved portions of the latch-arms 43, which latch-arms are secured together by means of bolts 44 extended through suitable openings in their rear ends and front portions. The front parts of the latch-arms 43 are diverged or flared, as is clearly shown in Fig. 2, so as to more readily engage the keeper 22 therefor on the front gate post.

As shown in Figs. 2, 3 and 4, the rear portions of the members 37 are provided with upwardly extended housings 45, through an opening in the upper parts of which is extended a locking handle 46, which has secured on its lower end a block or bolt 47, which operates partially in a vertical recess 48 in the rear portion of the circular or bearing part 42 of the bracket 36, and partially in vertical recesses 49, formed in the rear portion of the arms 43, at their adjacent or meeting edges. Each of the members 43 has a segmental recess 50, formed in its upper surface adjacent to its inner edge, at the rear portion thereof, and each of said members has in its front portion a recess 51 of sufficient size, when the members 43 are united, as shown in Fig. 4, to receive a portion of the bolt or block 47, which is normally pressed downwardly and held in engagement with the recess 48 of the rounded or bearing portion 42 of the member 37 of the bracket, and with the recesses 49, of the latch-arms, by means of a spring 52, which surrounds the vertical portion of the handle 46, and rests at one of its ends against the upper portion of the housing 45, and at its lower end against the block 47, which block or bolt normally holds the latching-arms 43 in their locked or normal positions, as shown in Figs. 1 and 2 of the drawings, but which may be released therefrom by raising the handle 46, in which operation the block 47 will be disengaged from the recesses therefor and permit the latch-arms 43 to turn to the position indicated by dotted lines in Fig. 2 of the drawings. After the handle 46 and block 47 have been raised to permit of the aforesaid movement, and said handle is released, the

spring 52 will depress the bolt or block 47, into one of the recesses 50 of the latch-arms, thus allowing the said arms to turn for a restricted movement, or until the block 47 engages one of the ends of said segmental recesses, in which position the latch-arms will be frictionally held until one of them strikes the keeper 22, on closing the gate, when it is apparent that said arms will be restored to their normal positions, and the bolt 47 will be shot or forced into the recesses therefor by its actuating spring. The recesses 51 are provided in the front parts of the arms 43, so that in shipping the latch said arms may be turned half way around on the bearing 42, when the bolt 47 will engage the recesses 51 and hold the arms 43 in substantial parallelism with the handle 46 of the bracket.

In adjusting the gate to an angular position with respect to the ground so as to permit small animals to pass under the bottom rail of the gate, yet to keep out larger animals, the front part of the gate may be lifted, when the parts will assume about the positions shown by dotted lines in Fig. 1 of the drawings, in which operation it is obvious that as the arms 43 of the latch stride the keeper 22, they will be free to move upwardly on said keeper, yet in such a manner as to hold the gate in its closed position. Before this raising can be done, however, the attachment for rigidly holding the frame must be suitably manipulated. This attachment consists of a link or bar 53, which has its upper end pivotally connected to the upper end of the front bar 25, of the gate, (but in the present instance it is shown so connected to the cap 33 on said bar), and a yoke 54 pivotally supported on the lower end of the bar 53 and embracing the top rail 27 of the gate. The opening 55 of the yoke or member 54 is of sufficient size to loosely encompass the rail 27, and said member has in the upper and lower portions of its opening 55 a movably located biting or gripping member 56, which is preferably made of hardened metal or steel and rectangular in cross section. The lower portion of the bar or link 53 is provided with a depending projection 57, located directly in front of the upper portion of the yoke or member 54, and is employed for the purpose of restricting the forward movement of said member. Extended across the lower portion of the link 53, in front of the projection 57 thereof is a spring 58, which is bent over the pivot 59, which connects the upper portion of the yoke or member 54, with said link, and has its lower portion in engagement with the yoke to normally hold the same in about the position shown by continuous lines in Fig. 6 of the drawings.

Instead of equipping the lower portion 65 of the link 53 with a spring of the above

mentioned construction, a projection 57^a, having a socket 58^a and a coiled spring 58^b, located in said socket, and resting against the front upper portion of the yoke or member 54, may be employed for the same purpose. Now, assuming that the parts are in the positions shown by continuous lines in Figs. 1 and 6 of the drawings, and it is desired to raise the gate to its angular adjusted position, it will be necessary to move the yoke or member 54 from the position shown by continuous lines in Fig. 6, to about the position shown by dotted lines in said figure, when it is apparent that the flat surfaces of the biting or gripping members 56 80 will be presented to opposite surfaces of the rail 27, thus permitting the yoke and rail comparatively free movement with respect to one another, until the desired angle of the parts of the gate is reached, when it is 85 apparent the yoke or member 54 will be caused to assume about the position indicated by continuous lines in Figs. 1, 6 and 9, by reason of the pressure of the spring which actuates said yoke, and that the gripping members 56 will so engage the rail 27 as to hold the parts of the gate rigidly with respect to one another.

The rear end bar 26 of the gate is provided in its front surface with a series of 95 recesses 60, located one above the other, for the purpose of engaging a holding member of the adjustable hinge, which holding member 61 is by preference horse-shoe-shape and provided with an opening 62, somewhat 100 larger than the gate bar 26, but by preference of a corresponding shape. The front portion of the holding member 61 of the adjustable hinge is provided with a transverse portion 63, and opposite said portion 105 said member is provided with a projection 64, extended at right angles from the member 61, or substantially so, to rest on the upper surface of the bracket 24, which is secured to the fence post 21, at the rear end 110 of the gate. The bracket 24 is by preference angular, as shown in Figs. 10 and 11, and its vertical portion is provided with a plurality of vertical slots 65, to receive bolts 66, extended through said slots into the post 21, 115 at the rear end of the gate. By this arrangement, it is obvious that if it is desired to raise the gate body the holding member 61 of the adjustable hinge can be loosened from one of the recesses 60 of the gate bar 26, so that said bar can be moved with the gate to any desired height, in which operation the holding member 61, will assume about the position shown by dotted lines in Fig. 10, until the extension 64 of said member is allowed to rest on the ledge or horizontal portion of the bracket 24, when it is obvious that said member will engage at its front portion one of the recesses 60 of the bar 26, and at its rear portion the rear part 120 125 130

of said bar, thus holding said post and the gate at the desired height with respect to the ground. Another hinge member 24, shown in Fig. 13, which may be of the same construction as the bracket 24, shown in Figs. 10 and 11, of the drawings, may be employed to hold and guide the lower part of the gate bar 26, and for this purpose, like the bracket 24 of the first described construction, is provided with a circular opening 67 for the reception of the rear gate bar. As this lower hinge member does not support the adjustable holder 61, the horizontal ledge or flange thereof may be reduced, or, in other words, it may be cut away as indicated by the dotted lines 68 in Fig. 13 of the drawings.

In order to unite and brace the upper and lower rails 27 and 28 respectively, of the gate at about their middle portions, and yet to allow them slight movement at said points, necessary in adjusting the gate to its angular position with respect to the ground, a truss-brace bar is employed, which consists of two oppositely and slightly bowed members 69 and 70, one of which is located on each side of the rails 27 and 28 and are by preference in cross section semi-circular as shown in Fig. 15 of the drawings. These bars are secured together by means of bolts 71, above and below the rails 27 and 28, as is clearly shown in Fig. 14, and thus firmly clamp and support said bars in a truss-like manner.

Having thus fully described my invention what I claim as new and desire to secure by Letters Patent is—

1. In a gate, the combination with a front end bar and a rear end bar, of upper and lower rails pivotally connecting the end bars, a link pivotally connected at one of its ends to one of the end bars, a spring actuated member loosely embracing one of said rails and pivotally connected to the other end of said link.

2. In a gate, the combination with a front end bar and a rear end bar, of upper and lower rails pivotally connecting the end bars, a link pivotally connected at one of its ends to one of the end bars, a member pivotally connected at one of its ends to the other end of said link and having parts extended

above and below said rail, and a gripping or biting member interposed between each of the said upper and lower parts and the rail.

3. In a gate, the combination with a front end bar and a rear end bar, of upper and lower rails pivotally connecting the end bars, a link pivotally connected at one of its ends to one of the end bars, a spring actuated member loosely embracing one of said rails and pivotally connected to the other end of said link, and biting members interposed between the upper and lower parts of the last named member and said rail.

4. In a gate, the combination with a front end bar and a rear end bar, of upper and lower rails pivotally connecting the end bars, net work located in the space bounded by said rails and bars and connected to said end bars and rails a truss-brace comprising a pair of members extending transversely of said upper and lower rails with one on each side thereof, said members being slightly bowed co-extensive of their lengths from each other, and clamping means positioned above and below each of the rails to hold said brace-members in engagement with said rails at substantially one point on each side thereof to provide a movable connection between the brace and rails.

5. In a gate, the combination with a front end bar and a rear end bar, of upper and lower rails pivotally connecting said end bars, net work located in the space bounded by said rails and bars a pair of members substantially semi-circular in cross section extended transversely of said upper and lower rails with one on each side thereof, said members being slightly bowed co-extensive of their lengths from each other and presenting their flat surfaces to said rails and a pair of bolts extended through said members, one of said bolts above and the other below each of the rails to hold said brace-members in engagement with said rails at substantially one point on each side thereof to provide a movable connection between the brace and rails.
